UNITED STATES PATENT OFFICE.

THOMAS J. GEORGE, OF INGLEWOOD, NEW JERSEY.

BUILDING CONSTRUCTION.

971,035.

Specification of Letters Patent. Patented Sept. 27, 1910.

Application filed November 5, 1907. Serial No. 400,853.

To all whom it may concern:

Be it known that I, THOMAS J. GEORGE, residing at Inglewood, in the county of Bergen and State of New Jersey, have invented certain new and useful Improvements in Building Construction, of which the following is a full, clear, and exact description, such as will enable others skilled in the art to which it appertains to make and use the same.

This invention relates to building construction.

One of the objects thereof is to provide a strong rigid supporting element of building construction of a simple and practical character.

Another object is to provide a structure of the above type of light weight and substantially fireproof character.

Another object is to provide means of the above type adapted to stand a heavy load without the use of beams or the like projecting beyond its surface.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawing, wherein is shown one of various possible embodiments of this invention, Figure 1 is a plan thereof. Fig. 2 is a side elevation. Fig. 3 is a similar view showing a complete floor section in either direction. Fig. 4 is a similar view of a slightly different embodiment of certain features of this invention.

Similar reference characters refer to similar parts throughout the several views of the drawings.

In order that certain features of this invention may be the more readily and fully understood, it may here be noted that in modern building construction, and more particularly in commercial buildings of the great sizes now common, there is a tendency to impose heavy loads upon the floors, thus requiring great strength to meet the same with a proper factor of safety. If it be attempted to gain this strength by the use of extraneous supporting means, as beams or the like, there results not only an unsightly construction, but an undue consumption of

space, where space is often highly valuable. It may also be noted that there is at present a broad and growing demand for buildings which are not susceptible to destruction by fire. In the attempt to meet this demand there have been constructed many so-called "fireproof" buildings, but it has been found that upon the same being exposed to a large conflagration or a fire well started within them, they cannot be depended upon to resist the same as even the metal is warped and weakened, if exposed directly to the flames. The elimination of these defects and the provision of a strong, compact and thoroughly fireproof element of building construction, are among the leading aims of this invention.

Referring now to the accompanying drawing, there are shown a series of blocks preferably arranged side by side substantially in a single plane, as indicated in Fig. 1. It is to be noted that in this illustrative embodiment the invention is shown as applied to floor construction to which use it is peculiarly adapted, but it is to be understood that many of the features thereof are of value in wall construction and other relations. These blocks are preferably formed as best shown in Fig. 2 of the drawing, having projecting portions 1 at their lower edges adapted to abut against one another, and providing spaces 2 between the remainder of their surfaces. These spaces are preferably of a zigzag conformation as shown, and extend entirely to the top of the block. It may here be noted that the term "block" is used broadly throughout this description and the following claims, to indicate any member adapted to resist compression, irrespective of its shape, although many advantages are found in the shape herein set forth. Considering now a group of these blocks as consecutively numbered from 3 to 18 inclusive, there is passed about the lower portions of blocks 3, 4, 9 and 10, a tension member 19 which preferably takes the form of an iron band set into appropriate recesses in the blocks, in order to lie substantially flush with the surface. At the upper portion of these same blocks, a similar band 20 passes about the same and holds them in the desired relation. About the blocks 5, 6, 7 and 8 similar bands are passed, as well about the blocks 11, 12, 17 and 18 and the group 13, 14, 15 and 16. Each of these blocks is thus rigidly held against outward move-

ment of either the upper or lower portions, and the crevices 2 are filled with cement in order to make a solid mass of the same and do away with any tendency of the blocks to swing one toward the other at their upper ends. There are also provided bands 21 similar to the bands 19 and 20, which are stretched about the upper and lower portions of the blocks 9, 8, 13 and 12. In this manner the four groups or sets, which were first pointed out in detail, are bound one to another, and it is to be understood that this construction may extend indefinitely, and each group be bound to the contiguous groups upon all sides. For example, the bands 22 pass about the blocks 4 and 5, as well as other blocks, which would be positioned at the side of these, and the block 6 is connected as by the bands 23 with other blocks, which would rest adjacent the same if the construction is to be continued in that direction. If this structure be used as a floor element there will remain blocks which abut against the wall or equivalent member upon each side, and it is to be understood that the same may be tied to the wall by bands similar to those shown and described. Considering the sets of two as 3 and 4 in one set, and 5 and 6 in another set, it is to be noted that a tension member passes about the members 3 and 4, another tension member about the blocks 5 and 6 and a third tension member about the blocks 4 and 5. These tension members, in this illustrative embodiment, also pass about other blocks, but it is to be seen that a single band may, if desired, be readily built up under this principle by binding the blocks only in sets of two in a longitudinal direction. It will also be seen that sets of three, or other numbers, might readily be connected under this principle, but many advantages are found in the type of construction shown in this embodiment.

Referring now to Fig. 3 there is shown a complete floor section extending between the abutments or supports 24 and columns 25. In this construction it will be noted that as the blocks approach the points of support, the tension members or bands are inclined upwardly as at 26, the degree of inclination becoming greater with each succeeding set of blocks as clearly indicated in the drawings. The final band or tension member 27, moreover, is preferably passed about the column 25, thus binding the same securely in place. It is also to be understood that the bands may be similarly inclined in a transverse direction, that is in a direction toward or away from the plane of the drawings it being unnecessary to illustrate this as the same will be obvious from the construction shown. By reason of this arrangement of the bands or tension members 65 the points at which the greatest shearing

stresses occur, namely adjacent the points of support, are provided with additional means for meeting these stresses, namely the lower tension members which by reason of their inclined position resist not only the bending 70 but shearing stresses of the floor as a whole. Thus, any force tending to thrust one of the blocks downwardly with reference to the contiguous blocks is met by the inclined tension members binding these together as well 75 as by the cement positioned between them, and the former tend to swing the blocks closer together and prevent relative displacement.

Considering the assembling of this construction as a whole, if the same is to be used as a floor, the blocks are mounted as upon a temporary scaffold with the lower portions abutting against one another, either directly or with a thin layer of cement therebetween, and the iron hoops or bands set in position. The crevices 2 are then filled with cement or the like to the upper surface of the floor, and upon the same hardening, a rigid monolithic mass results which possesses 90 a high degree of strength and rigidity without the use of supporting beams or girders, or any parts projecting beyond its surface. It will also be seen that the metallic members are thoroughly protected against fire, the 95 blocks being preferably of terra cotta or the like, and the entire mass is thus well adapted to withstand the most severe exposure to flames. The lower surface, moreover, forms a smooth ceiling, and it is to be noted that the term "floor" as used throughout is intended to comprehend ceiling construction. It may also be noted that the expression "pass about" is used throughout in its accurate sense as meaning embracing or extending around, and that the term "continuous" is intended to denote a form, by virtue of which the member described is continuous in effect though not necessarily integral. It 105 will also be seen that the construction may be arched in either or both directions and thus additional strength gained and, if desired, a vaulted ceiling formed. Such a construction is indicated in Fig. 4 of the drawings in which the blocks are arched as along the line 28, and the upper surface or floor is rendered level as by a cement filling 29. It will thus be seen that I have provided a construction in which the several objects of this invention are attained, and the above 110 enumerated advantages are, among others, present. The construction is simple, inexpensive and readily assembled, and when in position is not only compact and presents a neat appearance, but it is strong and rigid and well adapted to withstand the severe 115 conditions of practical use.

As many changes could be made in the above construction and many apparently 120 widely different embodiments of this invention 125

tion could be made without departing from the scope thereof, it is intended that all matter contained in the above description or shown in the accompanying drawings shall 5 be interpreted as illustrative and not in a limiting sense. It is also to be understood that the language used in the following claims is intended to cover all of the generic and specific features of the invention herein 10 described and all statements of the scope of the invention which, as a matter of language, might be said to fall therebetween.

Having described my invention what I claim as new and desire to secure by Letters 15 Patent is:—

1. In building construction, in combination, a plurality of sets of blocks, tie-members secured about and binding together the blocks of certain of said sets, and tie-members 20 secured about and binding together a plurality of blocks comprising a block of each of said last sets and a block of another set.

2. In building construction, in combination, a plurality of sets of incombustible blocks, a metallic tie-member secured about and binding together the blocks of each of said sets, and a metallic tie-member secured 25 about and binding together a block of each 30 of said sets and a block of another set.

3. In building construction, in combination, a plurality of pairs of blocks arranged side by side to form a substantially continuous surface, a tie-member secured about and binding together each pair, and other tie-members secured about and binding together a block of each pair and a block of another pair, each of said tie-members being 35 complete in itself, and connected to itself 40 about said blocks.

4. In building construction, in combination, a plurality of sets of blocks arranged side by side to form a portion of a floor, continuous tie members secured about the 45 lower portions of each of said sets, and continuous tie members secured about the lower portion of a member of each of said sets and a member of another set, said members being substantially in contact with said 50 blocks throughout their length.

5. In building construction, in combination, a plurality of blocks arranged side by side to form a portion of a floor, a tie member secured about the lower portions of two 55 of said blocks, and a separate tie member secured about the lower portion of one of said two blocks and another of said blocks adjacent thereto, each of said tension members being complete in itself and connected to 60 itself about said blocks.

6. In building construction, in combination, a plurality of sets of blocks arranged side by side to form a portion of a floor, tie members secured about and binding together 65 the lower portions of each of said sets of

blocks, and tie members secured about and binding together a block of each of said sets and a block of another set at their upper and lower portions.

7. In building construction, in combination, 70 a plurality of sets of blocks arranged in a single plane, a continuous tie-member secured about and binding together each of said sets, and a continuous tie-member secured about and binding together one block 75 of one set and one block of each of a plurality of other sets.

8. In building construction, in combination, 80 a plurality of sets of blocks arranged side by side in a single plane, a continuous tie-member secured about and binding together each of said sets and a continuous tie-member secured about and binding together a block of one set, a block of a set laterally offset in one direction with respect thereto, 85 and a block of a set laterally offset in another direction with respect thereto.

9. In building construction, in combination, 90 a plurality of sets of four blocks arranged substantially in a single plane, binding means secured about each of said sets of four blocks, and separate binding means secured about a block of each of three of said sets of four blocks, each of said means being complete in itself and connected to 95 itself about said blocks.

10. In building construction, in combination, 100 a plurality of sets of four blocks arranged substantially in a single plane, a continuous tie-member secured about and binding together each of said sets of four blocks, and a continuous tie-member secured about and binding together a block of each of three of said sets of four blocks, two of said sets being laterally offset with reference one to 105 another in one direction, and two of said sets being laterally offset with reference to one another in another direction.

11. In building construction, in combination, 110 a plurality of sets of blocks arranged substantially in a single plane, continuous tie members secured about and binding together the lower portions of each of said sets, and a continuous tie member secured about and binding together the lower portion 115 of one block of one of said sets, one block of a set laterally offset in one direction and one block of a set laterally offset in another direction.

12. In building construction, in combination, 120 a plurality of sets of four blocks arranged substantially in a single plane, tie members secured about and binding together the upper and lower portions of each of said sets, and tie members secured about and binding together the upper and lower portions of one block of each of four of said sets.

13. In building construction, in combination, 130 a plurality of sets of blocks arranged

side by side to form a portion of a floor and having their lower portions substantially in contact and their remaining portions spaced one from another a filling between said spaced portions, continuous tie members secured about and binding together the blocks of each of said sets, and continuous tie members secured about and binding together a block of each of said sets and a block of another set.

14. In building construction, in combination, a plurality of sets of blocks arranged side by side to form a portion of a floor and having their lowermost portions substantially in contact and their remaining portions spaced one from another, a filling between said spaced portions, a continuous tie-member secured about and binding together the blocks of each set, and a continuous tie-member secured about and binding together one block of one set and one block of each of two other sets.

15. In building construction, in combination, a plurality of sets of blocks arranged side by side to form a portion of a floor and having their lowermost portions substantially in contact and their remaining portions spaced one from another, a filling between said spaced portions, a continuous tie-member secured about and binding together the blocks of each set, and a continuous tie-member secured about and binding together one block of one set and one block of each of two other sets, said two other sets being respectively offset in two directions from said first set.

16. In building construction, in combination, a plurality of sets of four blocks arranged side by side to form a portion of a floor and having their lowermost portions substantially in contact and their remaining portions spaced one from another a filling between said spaced portions, a tie member secured about and binding together the lower portions of each of said sets of blocks, and a separate tie member secured about and binding together the lower portions of one block of each of four of said sets, each of said tension members being complete in itself and connected to itself about said blocks.

17. In building construction, in combination, a pair of supporting means, a plurality of members arranged side by side to form a portion of a floor extending from one to the other of said supporting means, tie means secured about and binding together two of said members, and tie means secured about and binding together one of said two members and another of said members and inclined upwardly from the center of said portion of the floor toward one of said supporting means.

18. In building construction, in combina-

tion, a pair of supporting means, a plurality of sets of blocks arranged side by side to form a portion of a floor extending from one to the other of said supporting means, tie members secured about and binding together the lower portions of each of said sets, and tie members secured about and binding together the lower portion of a member of each of said sets and a member of another set and upwardly inclined from the center of said portion of the floor toward one of said supporting means.

19. In building construction, in combination, a pair of supporting means, a plurality of sets of blocks arranged side by side to form a portion of a floor extending from one to the other of said supporting means, tie members secured about and binding together the lower portions of each of said sets, and tie members secured about and binding together the lower portion of a member of each of said sets and a member of another set and upwardly inclined from the center of said portion of the floor toward one of said supporting means, the degree of inclination of said last tie members being proportionate to their proximity to the corresponding supporting means.

20. In building construction, in combination, a pair of supporting means, a plurality of sets of blocks arranged side by side to form a portion of a floor extending from one to the other of said supporting means, tie members secured about and binding together the lower portions of each of said sets, and tie members secured about and binding together the lower portion of a member of each of said sets and a member of another set and upwardly inclined from the center of said portion of the floor toward one of said supporting means, the degree of inclination of said last tie members being proportionate to their proximity to the corresponding supporting means.

21. In building construction, in combination, a plurality of incombustible blocks arranged side by side, tension members respectively extending about and binding together each of a plurality of sets or groups of said blocks, and tension members respectively extending about and binding into groups or sets blocks from a plurality of said first sets, whereby said first sets of blocks are held in rigid relation one to another.

In testimony whereof I affix my signature, in the presence of two witnesses.

THOMAS J. GEORGE.
